UNITED STATES PATENT OFFICE.

WILLIAM C. MEYER, OF BEVERLY, MASSACHUSETTS, ASSIGNOR TO UNITED SHOE MACHINERY CORPORATION, OF PATERSON, NEW JERSEY, A CORPORATION OF NEW JERSEY.

WAX-THREAD SEWING MACHINE.

Original application filed April 28, 1917, Serial No. 165,107. Divided and this application filed September 6, 1918. Serial No. 252,970.

To all whom it may concern:

Be it known that I, WILLIAM C. MEYER, a citizen of the United States, residing at Beverly, in the county of Essex and State of Massachusetts, have invented certain new and useful Improvements in Wax-Thread Sewing Machines; and I do hereby declare the following to be a full, clear, and exact description of the invention, such as will enable others skilled in the art to which it appertains to make and use the same.

This invention relates to wax thread sewing machines and, more particularly, to take-up mechanisms for such machines.

The invention is particularly designed to be applied to chain stitch machines for sewing inseams of shoes, and is illustrated in this application as embodied in such a machine. The invention is not to be regarded as limited, however, to machines of this particular class but certain features thereof may be applied to other machines.

The primary object of the present invention is to produce a wax thread sewing machine having a take-up mechanism which may be readily regulated to operate in a certain reliable and improved manner on threads having different degrees of elasticity.

With this object in view, the invention consists in certain novel and improved constructions, arrangements and combinations of parts hereinafter described and particularly pointed out in the claims, the advantages of which will be obvious to those skilled in the art.

This application constitutes a division of application Serial No. 165,107, filed April 28, 1917, and in the accompanying drawings the invention is illustrated as embodied in the machine forming the subject-matter of said application.

The features of the invention will be readily understood from the accompanying drawings illustrating the invention in its preferred form, and the following detailed description of the constructions therein shown.

In the drawings, Fig. 1 is a view in side elevation of a machine embodying the invention illustrating a portion of the head of the machine with certain parts of the frame removed to show more clearly the structure. Fig. 2 is a detail plan view, partly in section,

illustrating the take-up mechanism; Fig. 3 is a view in side elevation of the mechanism shown in Fig. 2; Fig. 4 is an under side plan view illustrating a portion of the mechanism shown in Figs. 2 and 3; Fig. 5 is a view in side elevation of the mechanism shown in Fig. 4; Fig. 6 is a view similar to Fig. 5 illustrating certain of the parts in different positions; and Fig. 7 is a detail sectional view taken substantially on the line 7—7 of Fig. 6.

The machine illustrated in the drawings is provided with a curved hook needle 2, a feed point or awl 4, a looper 6, a tension wheel 7, a channel guide 8, a back gage 10 and a back rest 12. All of these parts have the same construction, arrangement and mode of operation as the corresponding parts of the machine illustrated and described in applicant's application referred to above, and a further description of the same in this application is unnecessary.

The take-up as herein illustrated consists of a roll 16, mounted on the forward end of an arm 18, carried by a lever 20 pivoted on a stud 22. The lever 20 is actuated from a cam 24 (Fig. 1) pivoted on a stud 26, the arm 28 of which carries a block 29 pivoted on its forward end and engaging in a slot 30 in the rear end of the lever 20. The other arm 31 of the cam lever carries a cam roll 32 engaging in a cam groove in a cam disk mounted on the main shaft 34. The arm 18 is pivoted on a stud 35 secured in the forward end of the lever 20, the rear end of the arm fitting between flanges 36 formed on the forward end of the lever 20, to prevent lateral play of the arm relative to the lever. The arm is acted upon by a spring 38 coiled about the stud 35 and having one end engaged beneath a pin 40 mounted on the arm, and the other end engaged beneath a pin 42 mounted on the lever 20. This spring tends to maintain the arm in its upper limiting position relative to the lever 20, with a stop face 46 formed on the arm in engagement with a stop face 48 formed on the lever.

The arm 18 is cut away at an angle to the stop face 46, as indicated at 50, so that the arm is enabled to swing downwardly, relatively to the lever 20, from its upper position. The downward swinging movement of the arm 18 relative to the lever 20 is limited by the engagement of an adjustable abut-

ment screw 52 threaded into a projection 54 on the arm with the stop face 48 on the lever. The abutment screw is held in adjusted position in said projection, by means 5 of a setscrew 56. The thread passes from the tension wheel 7 under a thread roll 58 mounted on the frame plate 59, then over the thread roll 16 and through the eye of the looper 6 to the work. The arm 18, when 10 free to swing relatively to the take-up lever 20, has the action of an auxiliary take-up or similar slack thread controller, said arm acting to control the slack in the thread during the first part of the retracting stroke of 15 the take-up lever. During the loop drawing stroke of the take-up lever the arm 18, under the resistance exerted by the thread, swings relatively to the take-up lever against the tension of the spring 38 until the abutment 20 screw 52 engages the stop face 48 on said take-up lever, after which the arm moves as one with the lever. During the first part of the retracting stroke of the take-up lever, the arm 18 swings in the opposite direction relatively to the lever 20 under the action of the 25 spring 38 until the stop face 48 on said arm engages the stop face 48 on the take-up lever, thus keeping the thread taut between the tension device and the work at this period in a 30 cycle of stitch-forming operations. At this time the looper is encircling the needle and laying the thread in the needle barb, and the action of the arm 18 in keeping the thread taut insures the proper threading of the 35 needle by the looper.

In sewing with thread, the elasticity of which is very slight, such as linen thread, it is found to be desirable that the arm 18 be arranged to operate as above described, to 40 control the slack in the thread and keep the thread taut during the first part of the retracting stroke of the take-up lever to insure the threading of the needle. In sewing with thread, however, the elasticity of which 45 is relatively great, such as cotton thread, it has been found that the stitches ordinarily will be tightened and set in a more uniform and reliable manner with the arm 18 secured rigidly to the take-up lever so as to move as 50 one therewith throughout both forward and retracting strokes of the take-up lever, and that the thread will be kept taut during the first part of the retracting stroke of the take-up lever by the elasticity of the thread 55 itself. To enable this latter result to be secured, mechanism is provided for locking the arm 18 rigidly to the take-up lever 20. In the construction illustrated, the locking mechanism for the arm 18 comprises a locking arm 60 pivoted on a boss 62 on the take-up lever 20, and constructed to embrace the lower part of the take-up lever as shown clearly in Figs. 2 and 7. The arm 60 is provided with a projection 64 constituting an 60 abutment for engagement with the upper

side or face of an abutment formed by a lateral projection 66 on the arm 18. When the arm 60 occupies the position shown in Fig. 6, with the projection 64 on said arm located to the rear of 70 the lateral projection 66 on the arm 18, said arm 18 is free to swing relatively to the take-up lever 20. To lock the arm 18 to the take-up lever 20, the arm 60 is swung forwardly and upwardly to locate the projection 64 thereon above the lateral projection 66, as shown in Fig. 5. With the arm 60 in the position shown in Fig. 5, the arm 18 will be held from swinging movement relative to the lever 20. In order to hold the arm 60 75 either in the position shown in Fig. 5, or that shown in Fig. 6, a retaining device is provided. This retaining device consists of a ball 68 mounted in a bore in the arm 60 and acted upon by a coiled spring 70, said ball being arranged to engage in either of the recesses 72 and 74 formed in the take-up lever 20. These recesses are so located that when the arm 60 is in the position shown in Fig. 6, the retaining ball 68 is engaged in 80 the recess 72, and when the arm 60 is in the position shown in Fig. 5, the ball is engaged in the recess 74. The retaining device will hold the arm 60 in either of its positions, but will permit the arm to be moved readily 85 from one of such positions to the other. The rearward movement of the arm 60 is limited by the engagement of the forwardly directed end of a projection 76 formed on the arm with the pin 42. This projection may also 90 serve as an operating handle for the arm 60 to be grasped by the operator in manipulating the arm.

Having explained the nature and object 95 of the invention and having specifically described a machine embodying the various features of the invention in their preferred forms, what is claimed is:

1. A wax thread sewing machine having, 100 in combination, stitch-forming devices including a hook needle, a looper, take-up mechanism comprising a take-up lever, an arm pivotally mounted on the forward end of the lever, a take-up roll carried by the arm, a spring acting on the arm and tending to swing the same in one direction relatively to the lever, a stop for limiting the movement of the arm relative to the lever under the action of the spring, and a locking device arranged when in one position to allow the arm to swing relatively to the lever, and when in another position to lock the arm 110 from movement relative to the lever.

2. A wax thread sewing machine having, 115 in combination, stitch-forming devices including a hook needle, a looper, take-up mechanism comprising a take-up lever, an arm having an abutment pivotally mounted on the forward end of the lever, a take-up roll carried by the arm, a spring acting on 120

the arm and tending to swing the same in one direction relatively to the lever, a stop for limiting the movement of the arm relative to the lever under the action of the spring, 5 and an adjustably mounted locking arm having an abutment arranged to engage an abutment on the roll-carrying arm to lock the

roll-carrying arm from movement in opposition to the action of the spring when the locking arm is in one position, and to be 10 located out of position to engage the abutment on the roll-carrying arm when said locking arm is in another position.

WILLIAM C. MEYER.
